ATTORNEY

UNITED STATES PATENT OFFICE.

KARL C. RANDALL, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

ELECTROMAGNETIC DEVICE.

1,241,554.

Specification of Letters Patent.

Patented Oct. 2, 1917.

Application filed March 23, 1914. Serial No. 826,555.

To all whom it may concern:

Be it known that I, KARL C. RANDALL, a citizen of the United States, and a resident of Edgewood Park, in the county of Allegheny and State of Pennsylvania, have invented a new and useful Improvement in Electromagnetic Devices, of which the following is a specification.

My invention relates to electromagnetic devices and particularly to single-phase electromagnets.

The object of my invention is to provide an efficient single-phase electromagnet which shall be noiseless in its operation.

Single-phase electromagnets, as ordinarily constructed, are noisy in operation, but, if a single-phase electromagnet is provided with a plurality of windings so designed as to exert their maximum forces at different times, substantially noiseless operation may be secured.

In the accompanying drawings, Figure 1 is a diagrammatic view of a single-phase electromagnet embodying my invention, Fig. 2 is a similar view of another form of a single-phase electromagnet adapted for noiseless operation, Fig. 3 is a diagrammatic view of a polyphase electromagnet adapted for noiseless operation, and Fig. 4 is a diagrammatic view showing the relations of the windings of the electromagnet shown in Fig. 1.

Referring particularly to Figs. 1 and 4 of the drawing, an electromagnetic device embodying my invention is connected to a single-phase circuit 1. The device is composed of two electromagnets 2 and 3 comprising, respectively, stationary core members 2^a and 3^a, movable core members 4 and 5 connected together by a rod 6, primary coils 7 and 8 connected in series relation, across the circuit 1, and auxiliary coils 9 and 10 of different numbers of turns that are connected together in a closed circuit.

When current flows through the coils 7 and 8, an electromotive force is induced in the coils 9 and 10, but, since the turns of the coils 9 and 10 are not equal, there will be a distortion in the magnetization of the two electromagnets. This distortion in the magnetization of the electromagnets will tend to cause the times at which the maximum pull occurs in the two electromagnets to be different. By properly arranging the

turns of the coils 9 and 10, one of the electromagnets may be made to exert its maximum pull substantially 90° out of phase with the other electromagnet, thus giving an electromagnet which is equivalent to a two-phase electromagnet. The advantage of this may be seen by those versed in the art, by reason of the fact that there is a pull on the movable members of the electromagnet system at all times. If there is a pull on the movable members at all times, the chatter which always accompanies the recurrent energizing and deenergizing of an ordinary single-phase electromagnet will be avoided.

The modification of my invention shown in Fig. 2 comprises two electromagnets 11 and 12 arranged in substantially the same manner as are the electromagnets shown in Fig. 1, with the exception that they are respectively wound with coils 13 and 14 which are connected to the secondary windings 15 and 16, respectively, of potential transformers 17 and 18. The winding 13 is connected in shunt relation also to a portion of the winding 16, for reasons hereinafter stated.

Since the coils 13 and 14 are not excited in the same manner, one being unbalanced with respect to the other, their magnetizing forces will be different. By properly changing the number of turns in the winding 16, to which the coil 13 is connected in shunt relation, the unbalancing may be increased to such an extent that one magnet will be exerting approximately its maximum pull while the other is exerting approximately its minimum pull, thus giving a resultant pull on the movable members thereof at all times and preventing the chattering that usually accompanies the use of a single-phase electromagnet.

Fig. 3 of the drawing shows two electromagnets 19 and 20 which are similar to the electromagnets 11 and 12 of Fig. 2 except that they are respectively provided with coils 21 and 22 connected in shunt relation to the conductors of a three-phase circuit 23.

Since the voltage of one phase of a three-phase circuit is out of phase with the voltages of the other phases, the coils 21 and 22 will exert their maximum magnetizing forces at different times, as will be understood by those versed in the art. It will be observed that the single-phase magnets 110

shown in Figs. 1 and 2 have operating characteristics and functions that closely resemble those of the polyphase magnet.

It is immaterial whether the primary windings of my invention are provided with different numbers of turns and the secondary windings are provided with the same number of turns, or whether the primary windings have the same number of turns and the secondary windings have different numbers of turns. It is also immaterial whether both primary and secondary windings have unlike numbers of turns. The essential requirement of my invention is that the ampere turns of each primary winding, when connected in series relation to the other primary winding, shall not be balanced by the resultant ampere turns of its secondary winding, when connected as hereinbefore explained with respect to Fig. 1, or the ratio of the turns of the coils of one electromagnet must necessarily be different from that of the turns of the coils of the other.

My invention is not limited to the particular construction illustrated but it is capable of various modifications within the scope of the appended claims.

I claim as my invention:

1. In an electromagnetic device, the combination with two stationary core members and two movable core members, of a primary winding for each pair of core members, and a secondary winding for each pair of core members, the ratios of the numbers of turns of the said windings on the respective pairs of core members being different.

2. An electromagnetic device comprising two stationary core members, two movable core members operatively connected together, main windings for the pairs of the said core members connected in series relation, and an auxiliary winding for each of the two pairs of core members, the effective ratios of the numbers of turns in the windings on the respective core members being different.

3. An electromagnetic device comprising two stationary core members having the same vertical axis, two movable core members mechanically connected together, coils for energizing the respective pairs of core

members, and auxiliary coils for the respective pairs of members, the effective ratio of the turns in one pair of coils being substantially different from that of the other pair. 55

4. An electromagnetic device comprising two magnetizable structures, main windings for the said structures connected in series relation, and auxiliary windings therefor, the effective ratio of the numbers of turns in the windings of one structure being substantially different from that of the numbers of turns in the windings of the other structure. 60

5. In an electromagnetic device, the combination with a plurality of electromagnets, of means for supplying single-phase electric current thereto, and means for so distorting the magnetizing forces of the said electromagnets that they attain their maximum 70 values alternately at intervals of substantially 90 electrical degrees.

6. In an electromagnetic device, the combination with a plurality of stationary core members, and a plurality of movable core members, of means for energizing the said core members with single-phase electric current, and means inductively related to said energizing means for exerting maximum magnetic force upon the said movable core 80 members alternately at intervals of substantially 90 electrical degrees. 75

7. In an electromagnetic device, the combination with a plurality of stationary core members, a plurality of movable core members, and magnetizing coils associated therewith, of means for energizing the said coils with single-phase electric current, and means for so distorting the magnetizing forces of the said electromagnets that they attain 90 their maximum values alternately at intervals of substantially 90 electrical degrees, substantially all of the ampere turns of the said coils being capable of exerting tractive force upon the said movable core members 95 at the said times of maximum magnetizing value.

In testimony whereof, I have hereunto subscribed my name this 19th day of Mar. 1914.

KARL C. RANDALL.
